UNITED STATES PATENT OFFICE.

LOUIS S. SPALLONE, OF DENVER, COLORADO.

FURNACE.

Application filed February 2, 1922. Serial No. 533,531.

To all whom it may concern:

Be it known that I, LOUIS S. SPALLONE, a citizen of the United States, residing at the city and county of Denver and State of Colorado, have invented certain new and useful Improvements in Furnaces; and I do declare the following to be a full, clear, and exact description of the invention, such as will enable others skilled in the art to which it 5 appertains to make and use the same, reference being had to the accompanying drawings, and to the characters of reference marked thereon, which form a part of this specification.

15 This invention relates to furnaces, and has special reference to improvements in hot air furnaces.

In many of the furnaces in common use the heat is not utilized to its fullest value, 20 due to the fact that no special effort has been made to obtain a good thermal efficiency.

It is the object of this invention to produce a furnace that shall be of simple and 25 substantial construction, which shall have a high thermal efficiency, and which shall be comparatively cheap to manufacture.

In order to attain the above objects, I construct my furnace in the manner which I 30 will now describe in detail, reference being had for this purpose to the accompanying drawing in which

Fig. 1 shows a front elevation of my furnace, with parts broken away to show the 35 construction and relative arrangement of parts;

Fig. 2 is a vertical section taken on line 2—2, Fig. 1;

Fig. 3 is a transverse section taken on line 40 3—3, Fig. 1;

Fig. 4 is a transverse section taken on line 4—4, Fig. 2; and

Fig. 5 is a view of one of my hot air registers.

45 The same reference numerals will be used to indicate the same or similar parts throughout the several views.

Numeral 1 represents the outer casing or drum of my furnace, and 2 an inner drum, 50 while 3 is the combustion chamber at the lower end of which is located the fire pot 4 and grate 5, below which is the ash pan 6. A passage 7 leads from the outside of drum 1 to the ash pan, and the front thereof is 55 closed by a door 8. A door 9 closes the outer end of a passage 10 which leads to the fire

pot and directly above passage 10 is a third passage 11 whose front end is closed by a door 12. Fuel is introduced through the door 9 and passage 10, and the gases and 60 other products of combustion leave through passage 11 and enter the helical flue 13 which makes one or more complete turns about the upper end of the combustion chamber, after which it passes to a point centrally of the 65 furnace where it extends out and into the chimney 14.

I want to call especial attention to the fact that the gas flue 13 has its inception at a point directly over the feed door entrance, as 70 this location of the flue seems to result in a better and more thorough combustion, and besides, it permits the clean-out door 12 to be placed vertically over the feed door 9 and the door 8 which leads to the ash chamber, 75 thus resulting in a convenient and pleasing arrangement. Inner drum 2 is spaced from the sides of the outer drum 1 by means of brackets 15, and its lower edge terminates a short distance from the base 16, in order that 80 air may pass from the space 17 between drums 1 and 2 and to the inside of drum 2, where it will come in contact with the hot flue 13 and the heated surface of the combustion chamber 3.

Near the tops of drums 1 and 2 I secure 85 my hot air pipe 18 and the return cold air pipe 19, the former opening into the space within drum 2 and the latter opening into space 17. Hot air pipe 18 is smaller than 90 pipe 19 and is held centrally of the latter by means of spacers 20.

Within the rooms to be heated the pipes 18 and 19 are connected to a specially designed register 21 which has a central opening 22 through which the hot air coming 95 through pipe 18 enters, and a space 23 through which the cold air enters into the space between the two pipes for return to the space 17 in the furnace, from whence it 100 passes downwardly until it reaches the lower edge of drum 2, after which it flows upwardly and into the hot air pipe 18, all as indicated by arrows in Fig. 1. It will be seen from the above that in my furnace a 105 continuous circulation of air takes place in the room, and that the cold air near the floor passes downward into the furnace, and in doing so it becomes heated to some extent from contact with pipe 18. Within drum 2 110 and between it and the combustion chamber 3 the air impinges on the hot flue 13 and

becomes highly heated, with the result that a high thermal efficiency is obtained.

In Fig. 4 I have shown a section which illustrates the manner in which drums 1 and 5 2 are spaced by member 15 and in which drum 2 is spaced from the combustion chamber 3 by means of spacers 24. On either side of my grate 5 I provide dampers 25 which have attached thereto a rod 26 by means of 10 which they may be opened and closed. When the ashes are removed or the fire shaken down, then the dampers 25 should be opened, permitting the ashes to pass upwardly into the combustion chamber instead 15 of into the furnace room, as is usually the case.

From the above it will appear that I have provided a hot air furnace that is simple in its construction and adapted to operate at a 20 high degree of thermal efficiency, and which can be manufactured and installed at a moderate cost. My furnace as pointed out above is so designed that it will remove the cold air from near the floor of the rooms at the 25 same time that the hot air enters, and thus provide a steady circulation of air, which will also insure that the room will be heated regardless of the direction of the wind outside or the relative air pressure in the various rooms to which the furnace is connected. 30

Having now described my invention, what I claim as new is—

1. A furnace comprising in combination

a central combustion chamber, a drum surrounding said chamber and spaced therefrom, an outer drum surrounding said last named drum and spaced therefrom, a fire pot in said combustion chamber, a feed entrance opening into said chamber, a gas flue opening located directly over the feed entrance, a 40 gas flue connected to the last named opening, said flue extending helically around the upper portion of the combustion chamber, and an air passage from the space between the two drums and the space surrounding the 45 combustion chamber.

2. A furnace comprising in combination a central combustion chamber, a drum surrounding said chamber and spaced therefrom, an outer drum surrounding said last 50 named drum and spaced therefrom, a fire pot in said combustion chamber, a feed entrance opening into said chamber, a gas flue opening located directly over the feed entrance, a gas flue connected to the last named opening, 55 said flue extending helically around the upper portion of the combustion chamber, an air passage from the space between the two drums and the space surrounding the combustion chamber, and a pipe leading from 60 the upper end of the inner drum to the room, and a pipe surrounding the first named pipe and spaced therefrom and extending from the space between said drum to the room.

In testimony whereof I affix my signature. 65
LOUIS S. SPALLONE.
